UNITED STATES PATENT OFFICE.

ISAAC STEIN AND SAMUEL STEIN, OF REVERE, MASSACHUSETTS.

HEEL LINING FOR BOOTS AND SHOES.

Application filed January 15, 1923. Serial No. 612,668.

To all whom it may concern:

Be it known that we, ISAAC STEIN, a citizen of the United States, residing at Revere, in the county of Suffolk and State of Massachusetts, and SAMUEL STEIN, a citizen of the United States, residing at Revere, in the county of Suffolk and State of Massachusetts, have invented new and useful Improvements in Heel Linings for Boots and Shoes, 10 of which the following is a specification.

This invention relates to a heel lining for boots and shoes and has for its object to provide a lining for the heel portion of boots and shoes, said lining being formed 15 in a single piece from any suitable flexible sheet material, preferably leather, said material being cut in such a manner that it may be folded and fashioned to fit the heel portion of a shoe upon the interior thereof 20 and utilized as an auxiliary lining where the original lining of the shoe has become worn and needs repairing or where the addition of a small amount of material at the heel portion of the shoe will improve the fit of the 25 shoe upon the foot of the wearer.

It is still further the object of the invention to so cut the blank from which the heel lining is constructed, that when the latter is formed, that a minimum amount of labor 30 will be required in cementing and stitching the edge portions thereof which require fastening.

The invention consists of a heel lining constructed and arranged as set forth in the 35 following specification and particularly pointed out in the claims thereof.

Referring to the drawings:

Figure 1 represents a plan view of the blank from which a heel lining embodying 40 our invention is formed.

Fig. 2 represents a perspective view of the finished heel lining.

Fig. 3 is a central longitudinal section 45 3—3 of Fig. 2.

Like numerals refer to like parts throughout the several views of the drawings.

In the drawings, 5 represents a blank formed in a single piece from any suitable 50 flexible sheet material preferably leather. The blank 5 is formed with a counter portion 6 which in the completed lining is located adjacent to the counter of the shoe and said counter portion 6 surrounds the 55 heel of the wearer at the sides and back of said heel. Formed integral with the counter

portion 6 are two sole portions 7, each of which is connected to the counter portion 6 by a neck portion 8. Each sole portion 7 is provided with a straight edge 9 which, after the lining is formed to fit the interior of a shoe, extends longitudinally of the sole portion of the shoe. The sole portions 7 are each provided with a curved end portion 10 which, after the lining is formed, constitutes the rear end of each sole portion. The lower edge of an intermediate portion of the blank 5 is provided with serrations 11 which extend from a point adjacent the inner end of the curved portion 10, said serrations 70 preventing any undue wrinkling of the material in shaping the lining.

In forming the blank 5 to fit the heel portion of a shoe, the sole portions 7 of said blank are bent upwardly at the neck portions 8 from the positions illustrated in Fig. 1, and the serrations 11 after having their upper surfaces covered with a suitable cementing material, are also bent upwardly approximately at 12, after which the intermediate portion of the blank is bent and the edges 9 of the sole portions 7 are abutted together and secured in any suitable manner, but preferably by stitches 13. The serrations 11 are now located beneath the rear end of the sole portion 7 adjacent to the curved rear edge 10 thereof, and the upper surface of said serrations are stuck to the under surface of the sole portion 7, as clearly illustrated in Fig. 3.

The lining, as hereinbefore set forth, may be constructed with a minimum amount of labor as there is only one seam which requires stitching and as this seam is centrally disposed and extends longitudinally of the completed lining, the stitching operation may be very easily and smoothly accomplished, while the serrations 11 allow the lower edge of the intermediate portion of the blank 5 to be secured beneath the sole portion without causing wrinkles or any other irregularities which would otherwise be uncomfortable to the wearer.

We claim:

1. A heel lining for a shoe formed of a single piece of flexible sheet material and embodying therein a counter portion and sole portions formed integral with said counter portion, said sole portions being stitched together longitudinally thereof.

2. A heel lining for a shoe formed of a single piece of flexible sheet material and

embodying therein a counter portion and sole portions formed integral with said counter portion, said sole portions being provided with curved rear ends and being 5 stitched together longitudinally thereof and means to secure a lower edge portion of said counter portion to the rear curved ends of said sole portions.

3. A heel lining for a shoe formed of a 10 single piece of flexible sheet material and embodying therein a counter portion and sole portions formed integral with said counter portion, said sole portions being provided with curved rear ends and being 15 stitched together longitudinally thereof to

form a centrally disposed seam, said counter portion being provided with serrations formed at its lower edge between said curved ends of said sole portions, said serrations being adapted to fold beneath said sole portions at said curved ends and means to secure said serrations to said sole portions. 20

In testimony whereof we have hereunto set our hands in presence of two subscribing witnesses.

ISAAC STEIN.
SAMUEL STEIN.
